(57) **CLAIM**

I claim the ornamental design for a remote controller for bidet, as shown and described.

DESCRIPTION

FIG. 1 is a perspective view of a remote controller for bidet showing my new design.

FIG. 2 is the front view thereof.

FIG. 3 is the rear view thereof.

FIG. 4 is the left side view thereof, with the right side view being a mirror image thereto.

FIG. 5 is the top plan view thereof.

FIG. 6 is the bottom view thereof; and,

FIG. 7 is a rear perspective view thereof.
